(57) **CLAIM**

The ornamental design for a device for controlling microscope, as shown and described.

DESCRIPTION

FIG. 1 is a perspective view of a device for controlling microscope.

FIG. 2 is a front view of the device of FIG. 1.

FIG. 3 is a rear view of the device of FIG. 1.

FIG. 4 is a left side view of the device of FIG. 1.

FIG. 5 is a right side view of the device of FIG. 1.

FIG. 6 is a top view of the device of FIG. 1; and, FIG. 7 is a bottom view of the device of FIG. 1.

The ornamental design which is claimed is shown in solid lines in the drawings. In the drawings, the broken lines depict environmental subject matter only and form no part of the claimed design.
